To all whom it may concern:

Be it known that I, LOUIS C. HILLER, of Wallingford, in the county of New Haven and State of Connecticut, have invented and produced a new, original, and ornamental Design for a Candlestick; and I do hereby declare the following, when taken in connection with the accompanying drawings and the letters of reference marked thereon, to be a full, clear, and exact description of the same, and which said drawings constitute part of this specification, and represent, in—

Having fully described my invention, what I claim as new, and desire to secure by Letters Patent, is—

The ornamental design for a candlestick as herein shown and described. 30

In testimony whereof I have signed this specification in the presence of two subscribing witnesses. 35
